UNITED STATES PATENT OFFICE.

JAMES M. WRIGHT, OF BROOKLYN, NEW YORK.

SHAPING-MACHINE.

SPECIFICATION forming part of Letters Patent No. 434,039, dated August 12, 1890.

Application filed April 24, 1890. Serial No. 349,231. (No model.)

To all whom it may concern:

Be it known that I, JAMES M. WRIGHT, of Brooklyn, New York, have invented an Improved Shaping-Machine, of which the following is a specification.

This invention relates to various improvements in shaping-machines; and it consists in the features of construction more fully pointed out in the claims.

10 In the accompanying drawings, Figure 1 is a side elevation of my improved shaping-machine with the table removed. Fig. 2 is a front view thereof; Fig. 3, a vertical section through the table on line xx , Fig. 2; Fig. 4, a 15 section through the crossways on line yy , Fig. 2; Fig. 5, a side view of the clutch with the driving-pulleys in section; Fig. 6, an end view of the clutch; Fig. 7, a vertical central section through the friction-rocker; Fig. 8, a 20 bottom view of the cutter bar or ram; Fig. 9, a top view thereof, and Fig. 10 a vertical longitudinal section through the shifting-bracket a^6 .

The letter a represents the frame of the 25 shaping-machine.

b is the cutter-bar, reciprocating backward and forward.

c is the crossways, and d the table, all as usual.

30 e is the power-shaft, provided with worm e' , said worm engaging the worm-wheel f , keyed upon shaft f' . To this shaft are keyed beneath the cutter-bar two worm-wheels g , that engage a pair of racks g' , secured to the lower 35 face of the cutter-bar. The usual intermittent revolving motion being imparted to the work-shaft, the cutter-bar will be moved toward and away from the work-table, as usual.

In order to secure an even and uniform 40 sliding motion of the cutter-bar, I make the lower or working face of the racks g' of convex shape, being segments and having the curve of a true circle and with inclined teeth, as shown in Figs. 2 and 9. The racks have 45 convex teeth which are set at an angle to the longitudinal axes of the racks. A rack of this form should be used with a worm-wheel g , having a corresponding concave working-face. By this construction each tooth of the 50 wheel will gradually overlap the corresponding tooth of the rack, thus moving the rack

and cutter-bar with a smooth and uniform motion. The reciprocating cutter-bar operates the clutch that reverses the motion of the work-shaft.

55

a' are two loose pulleys on the work-shaft e , revolved in opposite directions.

a^{10} is an extra-sized large pulley on one of the two pulleys a' .

a^2 is the clutch sliding on shaft e and adapted to engage either pulley a' . The clutch is provided at the center with two beveled collars a^3 , which are engaged by the shifting-fork a^4 , the shaft a^5 of which passes through the shifting-bracket a^6 , and is there connected 60 to the shifting-lever a^7 , which is shifted by the stops a^8 on the cutter-bar b . The handle a^9 serves to shift the fork by hand. By means of the beveled collars a^3 , with which the clutch is provided, I am enabled to obtain a firm and 65 positive grip of the shifting-fork on the clutch. The shaft a^5 , that gives motion to the fork, is connected to the upper or closed end of the same. Through the lower or free ends of the fork-prongs on the opposite side of the work-shaft passes a screw a^{11} , as shown. If the contact-faces between fork and clutch should become worn, the screw a^{11} on the fork need only be tightened up in order to re-establish 70 the firm grip of the fork.

75

In order to impart to the table d the transverse feed sometimes required, a friction-rocker b^2 is placed upon shaft f' , between the wheel f and a disk b^3 .

Washers b^4 , of leather or other suitable material, are set into and secured to surface-grooves of the rocker and permit it to be tightly clamped in place by nuts b^5 . These washers cause the rocker to turn in the same direction and uniformly with the wheel and 85 shaft until stopped by contact with the stops b^6 b^7 . Thus no matter how long the stroke of the cutter-bar the travel of the rocker is always limited by the stops.

The rocker b^2 is provided with an arm b^8 , 90 to which is secured a perforated holder or clamp b^9 , through which passes the bar b^{10} of a pawl b^{11} , that engages a gear-wheel b^{12} , fast on transverse screw b^{13} . This screw is tapped into the lugs b^{14} , secured to the work-table d 100 and imparts motion to such table along the crossways according to the usual manner.

b^{15} is the threaded shank of the movable stop b^6 , which is screwed into a projection b^{16} of bracket a . By screwing the stop b^6 farther out or in the play of the rocker is increased or reduced in a very simple manner. When the cutter-bar moves away from the work, the rocker moves toward the movable stop. During this motion the pawl b^{11} engages the gear-wheel b^{12} , and thus causes the work-table to be fed along the crossways. During the reverse motion of the cutter-bar the pawl is automatically disengaged from the gear-wheel in the usual manner.

The advantage of my construction lies in the simple means of regulating the feed of the table, even while the machine is in motion, by the adjustable stop b^6 .

In order to permit the crossways to be raised or lowered, so as to change the elevation of the work-table, I have devised the following lifting-gear: A horizontal shaft c' , journaled in the crossways, may be revolved by a suitable handle broken off on left-hand side, Fig. 2. The shaft carries a worm c^2 , which engages a worm-wheel c^3 . The worm-wheel in turn is tapped and is screwed on a fixed upright screw-shaft c^4 . The upper part or hub c^5 of the worm-wheel bears against an eye of the bracket c^6 , projecting rearwardly from and secured to the crossways c and loosely embracing shaft c^4 . When the shaft c' is revolved, it will cause the gear-wheel c^3 to travel up or down the shaft c^4 . When traveling up, the hub c^5 will push the eye c^6 , and with it the crossways c upward. When traveling down, it permits the crossways to descend by its own weight.

The work-table has heretofore usually been made in one connected piece, and if the work was to be tilted the entire table had to be tilted. I have so constructed the table that only its top plate need be tilted, while the remainder of the table always retains its usual level position.

My table d is hollow, is open at the top and front and is provided with the hooks d^8 , that engage the crossways c . The table has two depressions or slots into which are fitted two lugs d^9 , on the under side of the top plate d' . This top plate is provided at the back end with the two lugs or projections d^9 , cast on the under side of the plate. Pins d^2 pass through perforations in the lugs d^9 , and the table d serves to pivotally connect the top plate to such table. At the front the plate d' has two slotted curved guide-links d^3 , that project into the hollow body of the table. The links d^3 embrace guide-screws d^5 , screwed into the table. The guide-screws and links allow only a true tilting motion of the table.

without lateral movement. Across the interior of the table there is a cross-piece d^6 , in which is screwed a screw-shaft d^7 , that may be turned by hand. The upper end of this shaft bears against the top plate d' , and by turning the shaft this plate may be tilted so as to assume any desired inclination.

A shaping-machine constructed according to my invention is simple in construction, is readily handled and adjusted, performs its work truly, and is not apt to wear out unevenly.

What I claim is—

1. The combination, in a shaping-machine, of a work-shaft carrying a worm with a gear-wheel engaging the worm, a shaft on which the gear-wheel is mounted, concave worm-wheels g on said shaft, and a cutter-bar having racks g' , the faces of which have the curve of a true circle with inclined teeth to engage wheels g , substantially as specified.

2. The combination, in a shaping-machine, of a work-shaft with a pair of loose pulleys, a sliding clutch on the shaft, having beveled collars a^3 , a reciprocating shaft a^5 , a fork connected at its closed end to said shaft and engaging the collars a^3 , and a screw a^{11} , passing through the free ends of the fork-prongs and adapted to draw such prongs together, substantially as specified.

3. The combination of a work-shaft having a worm e' , with a gear wheel f engaged thereby and mounted on shaft f' , a friction-rocker b^2 , also mounted upon said shaft, a pawl reciprocated by the friction-rocker, a gear-wheel b^{12} , engaged by the pawl and keyed on shaft b^{13} , and with a table d , in which the shaft b^{13} is screwed, substantially as specified.

4. The combination of work-shaft e , having worm e' , with the gear-wheel f , engaged by said worm and operating the cutter-bar, a friction-rocker b^2 , having surface-grooves, washers b^4 within said grooves, a clamp b^9 , secured to the rocker, a pawl for operating the cross-head and secured to said clamp and with a movable stop b^6 , having a threaded shank b^{15} screwed into the machine-frame, substantially as specified.

5. The combination of crossways c with horizontal shaft c' journaled therein, a worm c^2 on said shaft, a worm-wheel c^3 meshing into said worm and having hub c^5 , a fixed upright screw-shaft engaged by the worm-wheel and with a bracket c^6 on the crossways engaged by the hub, substantially as specified.
